UNITED STATES PATENT OFFICE.

FRANK J. CREQUE, OF CUYAHOGA FALLS, OHIO.

TOY BALLOON.

1,137,385.

Specification of Letters Patent. Patented Apr. 27, 1915.

Application filed November 12, 1914. Serial No. 871,742.

To all whom it may concern:

Be it known that I, FRANK J. CREQUE, a citizen of the United States, residing at Cuyahoga Falls, in the county of Summit and State of Ohio, have invented certain new and useful Improvements in Toy Balloons, of which the following is a specification, reference being had therein to the accompanying drawing.

- 10 This invention relates to certain new and useful improvements in toy balloons and more particularly to a construction of the valve for the same; the object being to provide a toy balloon which is so constructed that the valve is removable in order to allow the air within the bag to pass freely through the stem, a suitable sound-producing device being arranged within the stem, in order to produce a whistling sound.
- 20 Another and further object of the invention is to provide a balloon which is exceedingly simple and cheap in construction and one in which the bag can be maintained inflated as long as desired and by the removal of the valve plug, a whistling sound will be produced, thereby enabling the toy balloon to be used for the ordinary purpose of a balloon and to produce a sound, if so desired.
- 30 Other and further objects and advantages of the invention will be hereinafter set forth and the novel features thereof defined by the appended claims.

In the drawing—Figure 1, is a perspective view of my improved balloon; Fig. 2, is a longitudinal section through the stem showing in full lines, the balloon collapsed and in dotted lines, the balloon inflated; Fig. 3, is a perspective of the stem detached, partly in section, showing the plug carrying the sound-producing device; and Fig. 4, is a perspective of the plug valve, detached.

Like numerals of reference refer to like parts in the several figures of the drawings. In carrying out my invention, I employ an inflatable bag 1 preferably formed of rubber having a neck 2 which is adapted to be secured over one end of a tubular stem 3 by an elastic band 4; said stem being provided with an enlargement 5 at its end in order to enable the neck to be secured firmly in position over the tubular stem 3.

Arranged within the tubular stem 3 at the end carrying the inflatable bag, is a tubular plug 6 having its bore enlarged as shown at 7 over which is arranged an elastic

or flexible strip 8 which extends rearwardly in grooves formed in the circumference of the plug 6 and is secured in position by an elastic band 9 which forces the end portions 60 of the strip 8 within the groove 10 formed in the plug 6 to receive the band 9 in order to securely hold the elastic strip 8 taut across the open end of the tube. This produces a whistling sound by the air passing 65 through the plug 6 after the bag has been inflated in the well-known manner.

Arranged within the opposite end of the stem 3, is a valve plug 11 which is tubular in form and is provided with an annular flange 12 at its outer end forming a stop for limiting the inward movement of the plug within the stem and this flange also forms a mouth piece by means of which, the stem can be held within the mouth. The 75 flange enables the valve plug to be readily detached when desired and arranged, upon the inner end of the valve plug is a flat valve 13 formed of any suitable flexible material, non-pervious to air, so as to completely close the valve plug after the inflatable bag has been inflated by a person blowing into the stem through the valve plug. The pressure of air against the valve 13 when the bag is inflated closes the same 85 and maintains the same in closed position.

The operation of a toy balloon as herein shown and described, is as follows: Assuming that the balloon is in the position as shown in full lines in Fig. 2, a person inserts the stem within the mouth and by blowing through the stem, the valve is opened so as to allow air to pass into the inflatable bag in order to inflate the same, the pressure of air within the bag holding the valve in 95 closed position in order to allow the balloon to be used as an ordinary balloon and it is, of course, understood that the same can be secured to a stick, if desired. When it is desired to produce a whistling sound, the 100 plug 11 is detached carrying the valve, which allows the air within the inflatable bag to escape through the plug 6 and by the passage of air through the bore of the plug around the flexible strip 8, a whistling sound 105 is produced.

I claim:

1. A toy balloon, having a stem, a plug arranged within said stem having a sound-producing device, and a detachable valve 110 plug mounted in the outer end of said stem.
2. A toy balloon, having a stem provided

with a sound-producing device, and a detachable valve mounted within said stem.

3. A toy balloon, comprising an inflatable bag having a neck, a stem arranged within said neck, a tubular plug arranged within said stem having a strip of flexible material arranged over one end thereof, and a plug arranged in the opposite end of said stem, having a flap valve at one end.

10 4. As a new article of manufacture, a toy balloon, comprising an inflatable bag provided with a neck, a tubular stem secured

within said neck, a tubular plug mounted within said stem, a strip of flexible material arranged over the inner end of said tubular 15 plug, a flanged plug arranged within the outer end of said stem, and a flap valve mounted upon the inner end of said plug.

In testimony whereof I affix my signature in presence of two witnesses.

FRANK J. CREQUE.
